COOKING RANGE.

No. 15,426.

Patented Sept. 23, 1884.

UNITED STATES PATENT OFFICE.

WALTER E. PARFITT, OF BROOKLYN, ASSIGNOR TO THE SIMONDS MANUFACTURING COMPANY, OF NEW YORK, N. Y.

DESIGN FOR A COOKING-RANGE.

SPECIFICATION forming part of Design No. 15,426, dated September 23, 1884.

Application filed December 5, 1883. Term of patent 7 years.

To all whom it may concern:

Be it known that I, WALTER E. PARFITT, a citizen of the United States, residing in the city of Brooklyn, in the county of Kings and State of New York, have invented and produced a new and original Design for Cooking-Ranges, of which the following is a specification, reference being had to the accompanying cut, print, or engraving representing to said new design.

The general design for the range consists of the main body A and the elevated portion B, shaped and ornamented so as to present substantially the same appearance that is represented in the accompanying engraving.

The design for the main body A consists of the base-section C and the principal section D, shaped and ornamented so as to appear substantially as represented in the accompanying cut.

The design for the elevated portion B consists of the pilasters E and the top section F, shaped and ornamented so as to appear substantially as shown in the aforesaid print.

The design for the top section F consists of the upper-plate part G, having the lateral panels a and central panel, b, shaped and ornamented as shown, the oblong lower-plate portion H, having the rectangular end panels, c, with the ornaments d therein, and the rectangular doors I, having corresponding panels, e, furnished with the central ornaments, f, and outer ornaments, g.

The design for the pilasters E consists of the base h, column i, and cap j, all shaped and ornamented as shown.

The ornamentation of the rectangular door J on the principal section D consists of the representation of a fawn, k, standing with its face and one side to the front on an elevation, l, under an ornamental arch in the panel m, as shown.

The design for the rectangular fire-door K consists of the panel n, having the central ornament, o, the bottom semi-rosette ornamentation, and the upper corner ornaments, all shaped as shown.

The design for the base-section C consists of the bottom plate, L, top plate, M, and the upright plate N, having the alternating ornaments p and q, all shaped as shown.

I claim as new—

1. The design for a cooking-range, consisting of the body portion A and the elevated portion B, shaped and ornamented as set forth. 55

2. In a design for a range, the body portion A, consisting of the base-section C and principal section D, shaped and ornamented as set forth. 60

3. In a design for a range, the elevated portion B, consisting of the pilasters E and top section F, shaped and ornamented as set forth. 65

4. In a design for a range, the shape and ornamentation of the top section F, consisting of the parts G a b, H c d; and I e f g, as shown and described. 70

5. In a design for a range, the shape and ornamentation of the pilasters E, consisting of the parts h i j, as shown and described. 75

6. In a design for a range, the ornamentation of the rectangular front door, J, consisting of the representation of a fawn, k, on an elevation, l, under an ornamental arch on the panel m, as shown and described. 80

7. In a design for a range, the ornamentation of the rectangular fire-door K, consisting of the panel n, having the central ornament, o, the semi-rosette ornament at the bottom, and the upper corner ornaments, as shown and described. 85

8. In a design for a range, the configuration and ornamentation of the base-section C, consisting of the parts L M N p q, as shown and described. 90

In testimony whereof I hereunto set my hand, in the presence of two subscribing witnesses, this 20th day of November, 1883.

WALTER E. PARFITT.
